CLAIM

The ornamental design for a LED smart mini heat press, as shown and described.

DESCRIPTION

FIG. 1 is a front, top perspective view of a LED smart mini heat press, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is an exploded rear perspective view thereof.

[The broken lines show portions of the LED smart mini heat press that form no part of the claimed design.]

1 Claim, 9 Drawing Sheets
